UNITED STATES PATENT OFFICE.

FRANK A. KLOHS, OF MANSFIELD, OHIO, ASSIGNOR TO THE OHIO BRASS COMPANY,
OF MANSFIELD, OHIO, A CORPORATION OF NEW JERSEY.

REELING DEVICE.

1,366,189.

Specification of Letters Patent. Patented Jan. 18, 1921.

Application filed March 28, 1919. Serial No. 285,733.

To all whom it may concern:

Be it known that I, FRANK A. KLOHS, a citizen of the United States of America, residing at Mansfield, in the county of Rich-
5 land and State of Ohio, have invented cer-
tain new and useful Improvements in Reel-
ing Devices, of which the following is a
specification.

My invention relates to an automatic reel-
10 ing or winding device and has particular
reference to the retrieving and resetting
mechanism of such devices and I have de-
scribed its use and operation as applied to
spring actuated trolley retrievers although
15 its use is not limited to trolley retrievers
which are spring actuated or to other spring
actuated devices.

One object of my invention is to provide
a mechanism whereby the reeling apparatus
20 can be adjusted to any number of turns
within the capacity of the device.

Another object of my invention is to pro-
vide a construction in which the retriev-
ing mechanism is automatically "set" in its
25 locked position for action after a predeter-
mined number of turns has been given the
same in a spring winding direction.

Another object of my invention is to pro-
vide means whereby the locking mechanism
30 is maintained out of action during the reel-
ing-in or winding-up operation of the mech-
anism.

A further object of my device is to pro-
vide means whereby the locking or setting
35 of the reeling mechanism when rotated in
opposition to the spring winding tension
cannot be accomplished until the predeter-
mined number of turns of the reeling mech-
anism has been made.

40 As applied to trolley retrievers, a further
object of my invention is to provide means
whereby the trolley rope secured to the
trolley pole can be attached to my device in
such a way that a sudden rapid rise of the
45 trolley pole as in case of same leaving the
trolley wire, will automatically throw the re-
trieving mechanism into operation and draw
down or retrieve the trolley pole, but at all
other times the device will merely keep the
50 trolley rope taut.

This invention accordingly consists in the
features of construction, in combination of
parts and in the unique relation of the mem-

bers and in the relative proportioning and
disposition thereof, all as more completely
outlined herein.

To enable others skilled in the art to fully
comprehend the underlying features of this
invention that they may embody the same
in various forms contemplated by this in-
vention, drawings setting forth a preferred
form of my invention as applied to trolley
retrievers or tenders have been annexed as
a part of this disclosure, and in such draw-
ings like characters of reference denote cor-
responding parts throughout all the views.

Figure 1 is a view of a trolley retriever
embodiment of my invention and shown in sec-
tion to better illustrate the arrangement of
the several parts.

Fig. 2 is a sectional view taken on the line
2—2 of Fig. 1 and shows the relation of
such parts as this view will permit with the
retrieving mechanism in a locked position
ready to operate when the locking mecha-
nism is tripped.

Fig. 3 is a sectional view on the line 2—2
of Fig. 1 but shows the relation of parts
after the retrieving mechanism and reel
have been interlocked and the locking mech-
anism has been tripped and the reel has made
two complete revolutions in winding up the
rope.

Fig. 4 is a view taken on the line 2—2 of
Fig. 1 and corresponds to Fig. 3 excepting
some of the parts have been omitted in
order to avoid confusion and show more
clearly the relation of the main retrieving
parts or mechanism when the retrieving disk
and reel, locked thereto as in Fig. 3, have
made two complete revolutions.

Fig. 5 is a view taken on the line 2—2 of
Fig. 1 and shows the position of the lock-
ing slot in the ring gear 15 when the re-
trieving disk and reel are in the same rela-
tive position with respect to the casing as
in Figs. 3 and 4 but has made five complete
revolutions.

Fig. 6 is a view taken on the line 2—2 of Fig. 1 and shows the relation of the retrieving
parts after the rope has been unwound
from the reel, by pulling out the rope, thereby
rotating the retrieving disk in a rope-
unwinding direction a predetermined num-
ber of turns and in a direction to wind up
the retrieving spring and the rotation of the

retrieving mechanism has been automatically checked by the latch 35 engaging the locking slot in the ring gear 15.

Fig. 7 is a sectional view on the line 2—2 of Fig. 1 and corresponds to Fig. 2 except that the retrieving mechanism has been locked in operative position and the centrifugal dog is shown in the act of releasing from the retrieving mechanism.

Fig. 8 is a detail sectional view of the inner end connection of the retrieving spring.

Fig. 9 is a detail view showing the ratchet connection of the inner end of the service spring.

Fig. 10 is a detail sectional view on the line 10—10 of Fig. 6.

As I am describing my invention as applied to the trolley retriever I will set forth the objects and purposes of such a device before going into a detailed description of the particular construction set forth in this specification and drawings attached.

The trolley retriever as applied to electric cars has for its purpose first, to keep the trolley rope taut during normal operation of the car but to permit of free movement of the trolley pole up and down as it accommodates itself to the rise and fall in the trolley wire; second, in case of the trolley pole jumping the trolley wire as is frequently the case at overhead frogs, crossings and curves, the trolley retriever must quickly and positively draw the trolley pole down below the level of the trolley wire to prevent the trolley pole striking the overhead work and tearing it down.

In performing these two functions the device in itself must have certain characteristics, namely, automatic means for locking the rope drum or reel to the retrieving mechanism when the trolley pole makes an abnormal rapid upward movement; an automatic unlocking of the retrieving mechanism as quickly as possible when the upward movement of the trolley pole takes place; means whereby the retrieving mechanism can be adjusted to give and maintain any desired predetermined number of turns of the rope reel within the limits of the construction; means preventing the throwing of the retrieving mechanism in a locked or operative position before the predetermined number of turns has been made; means for positively indicating when the predetermined number of turns in resetting the retrieving mechanism has been reached and limiting further rotation; means preventing the reengagement of the retriever locking mechanism until the predetermined number of turns of the reel has been made in a rope-winding direction; means for automatically locking the retrieving device in a position for again retrieving after the reel and retrieving mechanism has been rotated in a

rope-unwinding direction for a predetermined number of turns. All of these characteristics are found in the device herein disclosed and my method of bringing about these characteristics will be brought out clearly in the following description.

First I have a case composed of two parts, namely the back indicated by numeral 1 and the removable front indicated by numeral 2. The rear of the back portion 1 is recessed with a cavity 3 in which is positioned a power spring 4. The outer end of this spring is attached to the case 1 by means of rivets, screws or other suitable means. The inner end of the spring is secured to a collar 5 which is provided with a plurality of slots or grooves 6 upon its interior surface for the reception of a projecting key or lug 7 upon the hub 8 as indicated. This lug or key engages with the slot 6 and allows the withdrawal of the member 9 without disturbing the spring and as the collar 5 has a plurality of slots 6 around the interior surface of the collar the construction permits of positioning the member 9 with respect to the spring 4 as may be desired and which is more fully explained hereinafter.

The hub 8 projects from the member 9 and this member 9 which is rotatably mounted upon a fixed shaft or spindle 10 is termed a retrieving disk or member.

Closing the chamber 3 is a diaphragm member 11 secured to the case 1 by means of the screws 12 or by equally satisfactory means. Projecting from the diaphragm 11 at one point is a stud 13 and rotatably mounted upon the stud 13 is a double gear 14, one part being indicated by 14A and the other part by 14B. Rotatably secured to the case 1 is an internally toothed ring-gear 15 which is held in position by suitable plates and screws 16 or by other suitable means. The pinion 14A meshes with the ring-gear 15 at the point X. Secured to the hub 8 of the retrieving disk 9 is another toothed member 17 and this toothed member rotates with the disk 9 and meshes with the gear 14B at the point Y.

The retrieving disk 9 is provided also with a boss 18 which might be considered a continuation of the boss 8, and upon the boss 18 is rotatably mounted a reel 19 to which the trolley rope leading from the trolley pole is secured. This reel 19 is free to rotate in either direction to maintain the trolley rope taut under normal operation and this is accomplished by the use of a spring 20 of low tension capacity in order that the same shall not interfere with the free rising and falling of the trolley pole with a change in the elevation of the trolley wire. One end of this spring is secured to the reel or drum by means of rivets 21, screws, etc., and the other end is secured by rivets, screws, etc., to a rotatable collar 22.

which is rotatably mounted upon a collar 23 which is pinned to the stud or shaft 10 as indicated by 24. The engaging edges of the members 22 and 23 are provided with 5 ratchet teeth at the point Z and these teeth are held in engagement by the spring 25. This combination forms a ratcheting means by which the tension of the spring 20 can be easily adjusted by rotating the member 22 10 with reference to the fixed member 23. The collar 23 also retains the various parts thus far named in position on the shaft 10.

Secured to the reel 19 are one or more centrifugally operated dogs 26 and under normal operation these dogs are held in a retracted position as indicated in Fig. 2 by 15 means of the spring 27, one end of which is attached to the dog and the other end to a pin 28 on the reel 19. The dog 26 is provided with a cylindrical end 29 adapted to be seated in a circular cavity of the lug 30 which is an integral part of and projects from the face of the reel 19. Under normal operating conditions the dogs are retracted 20 and the end faces of the dogs rest against the faces 31 of the support lugs 30. Should the trolley pole leave the wire at any time the rapid upward movement of the same will cause the reel 19 to revolve at such a rate as 25 to cause the dogs 26 to fly outward from centrifugal force as set up in opposition to the tension of the spring 27 and when in a thrown-out position one of the centrifugal dogs will pass under and trip the locking 30 dog 35 and then assume the position shown in Fig. 3 in which its end is in engagement with the shoulder 34 on the disk 9 and thereby locking the drum or reel 19 to the retrieving disk 9 as more clearly explained 35 hereinafter. A rib 33 is secured to the drum 9 for engaging a rib 32 on a dog to prevent the disengagement of the two members while 40 in an interlocked position. A latch 35 hinged at 36 to the case is held in engagement 45 with the retrieving mechanism by the spring 37 and is adapted to alternately engage the stop 38 on the disk 9 and the stop 39 on the ring-gear 15 as more fully hereinafter described. The rib 40 engages 50 the rib 32 on a dog 26 and insures the dog strongly contacting with the latch 35 in the operation of releasing the latch from the disk 9 and makes this operation positive.

Immediately upon the engagement of a 55 dog with the latch the retrieving mechanism is released and the power spring 4 tends to revolve the disk 9 in the direction of the arrow R and the rotation of the drum or reel 19 continues in the rope-unwinding direction 60 until the dog 26 engages the lug 34 as indicated in Fig. 3. This engagement of the dog with the lug 34 on the retrieving disk takes place almost immediately upon the disengagement of the latch 35 with the stop 38 65 of the retrieving disk.

The latch 35 is wide enough so as to engage the face of the stop 39 in the ring-gear 15 and the face 38 of the stop in the retrieving disk 9. The diameter of the ring-gear is made somewhat greater than the diameter of the retrieving disk 9 and this larger diameter assures the latch 35 being held out of engagement at all times with the disk 9 excepting at such time as the stops in the disk and ring-gear coincide under proper 70 condition.

The gearing 14A, 14B and 17 is for the purpose of rotating the ring-gear 15 at a certain rate relatively to the rotation of the retrieving disk 9 and the gearing is so arranged that the ring-gear 15 rotates in the opposite direction to the rotation of the retrieving disk 9. We will assume for convenience of description that in the device herein shown the arrangement of the gearing 80 is such as to permit the retrieving disk 9 to make six revolutions in one direction while the ring-gear 15 makes one revolution in the opposite direction. Since the members 85 15 and 9 are linked together by means of the gears 14 and 17, the relation between the members 9 and 15 is maintained; that is, there is no slippage of one part relatively to the other and after the retrieving disk 9 has made six complete revolutions the relation 90 between the disk 9 and the ring-gear 15 will be the same as at the instant when the disk 9 began to make its first revolution.

It will be readily understood that for one revolution of the retrieving disk the ring-gear 100 will make one-sixth of a revolution and for each additional revolution of the retrieving disk the ring-gear will be further advanced one-sixth of a revolution until at the end of six revolutions of the retrieving 105 disk the ring-gear will have made one complete revolution. It is therefore very easy to adjust the retrieving mechanism so that the reel to which the rope is attached when interlocked with the disk can be caused to 110 wind up the rope one or more revolutions within the limits of the device and this is accomplished by proper setting of the stop 39 of the ring-gear 15 with the stop 38 of the disk 9 with respect to a point where the 115 two notches coincide and which I will term the zero point and opposite the engaging point of the latch 35.

In order to make it possible to conveniently change the relation of the members 9 120 and 15 so as to adjust the number of revolutions of the drum and retrieving disk to meet a predetermined number of turns, I mark upon the case or other adjacent point, indicating marks which I have numbered 125 0-1¹-2¹, etc., to 5¹ inclusive and to set my retrieving device for any number of revolutions of the drum it is only necessary to set the face of the stop 39 of the ring-gear 15 opposite the indicating 130

mark showing the figure corresponding to the number of turns of the drum desired and then place the disk in position as shown in Fig. 1 and place the face of the stop 38 opposite the indicating mark 0. For instance in Fig. 3 the member 15 is shown as having the face of the stop 39 set opposite the indicator mark 2^1 and the face of the stop 38 on the retrieving disk 9 is set opposite the indicating mark 0 and with this setting the retrieving disk and drum will be given two revolutions when the drum is rotated in a rope-winding direction but not against a strong opposing force as later on explained, and when resetting the device and the drum is wound in a rope-unwinding direction and against the action of the power spring 4 the drum and the retrieving disk 9 will be given two full turns before the latch 35 engages with and locks the members in position for further retrieving action.

The plurality of slots 6 in the collar 5 permits of placing the retrieving disk 9 in different relations to the ring-gear 15 as desired without bringing any tension upon the spring 4. If there were only one slot 6 in the collar 5 then in setting the disk 9 in all but one relation to the ring-gear 15 the spring would be under tension and it would not be possible to properly adjust the device.

It will of course be understood that the ratio of gearing can be so proportioned that any number of turns of the disk 9 can be had, within reason, for one revolution of the ring-gear 15.

In Fig. 4 I have shown, with some parts missing, the same relation of the members 9 and 15 as shown in Fig. 3, namely the member 15 set at 2^1 and the member 9 set at 0 which gives the member 9 two turns. In Fig. 5 I have shown the setting of the member 15 to give five turns of the member 9 (not shown but positioned as shown in Fig. 4).

It is usual in setting my device to set the face of the stop 38 off somewhat from the zero point and this will then permit of a slight difference between the stop faces 38 and 39 when the disk is in a locked position as shown in Figs. 2 and 7 or as shown in Fig. 6 at the instant that the locking pawl has engaged the ring-gear 15 in resetting the retrieving mechanism. This distance can be made anything desired by placing the face of the stop 38 off from the 0 mark by the amount of difference desired.

I will now explain the functioning of the various parts of my device by outlining in sequence the operation of the device when brought into action as by a trolley pole suddenly leaving the trolley wire.

The rapid rising of the trolley pole will cause the rope to unwind from the drum 19 at an abnormal rate and this will set up in the dogs 26 a centrifugal force in excess of

that which the springs 27 are adjusted to overcome. The dogs 26 will fly outward and into engagement with the inner surface of the retrieving disk flange and the one which at the instant is nearest the rib 40 will be forced into engagement with the locking lug 35 and the engagement of the rib 32 with the rib 40 will positively insure the locking dog 35 being raised or thrown out of engagement with the stop 38 in the retrieving disk 9. The retrieving disk 9 will immediately start to rotate in the direction R indicated by the arrow under the action of the retrieving spring 4 and the reel or drum will continue to rotate in a rope-unwinding direction until the dog 26 and the shoulder 34 on the retrieving disk 9 engage and at that instant of engagement the rotation of the drum in a rope-unwinding direction will be arrested and reversed and the rope will then be wound upon the drum as the drum will be locked to the retrieving disk and held in a locked engagement by the rib 33 on the retrieving disk 9; the rib 33 also prevents disengagement of the members due to any rebound at the instant of a strong engagement of the dog and disk. The drum and disk will continue to rotate in a rope-winding direction until the two have completed the number of turns of a predetermined amount.

After the drum and reel have made the necessary number of turns in a rope-winding or retrieving direction indicated by the arrow R, these members will come to a rest but the dog 26 will still be held in engagement with the disk 9 as the upper pressure of the trolley pole through the rope will be constantly urging the dog 26 into engagement with the shoulder 34 and the rib 33 will maintain the dog 26 in engagement regardless of the position anywhere within a circle which the two may assume when at rest.

During the rotation of the drum and disk in a rope-winding or retrieving direction as indicated by R on the drum, the ring-gear 15 has rotated in the opposite direction as indicated by the arrow R on the ring-gear.

At the instant that the latch 35 is thrown out of engagement with the stop 38 on the disk 9 the disk begins rotation in the retrieving direction R as indicated upon the disk and before the disk has made one revolution the latch 35 will be riding upon the outer face 41 of the ring-gear 15 as shown in Fig. 3 and thereby permitting the retrieving disk 9 to complete its predetermined number of revolutions without danger of reengagement of the latch 35 with the locking face 38 on the disk 9.

To reset my retrieving mechanism it is only necessary to pull the rope out of the device, causing the drum to rotate and with it the disk 9 to which it is interlocked as explained. The rotation of the disk 9 will be

in the setting direction indicated by the arrow S and coincidentally the ring-gear 15 will rotate in the direction of the arrow S as shown on the ring-gear and which direction 5 is opposite to that of the disk 9. After the same number of turns has been made by the disk in unwinding the rope from the reel as was made by the disk in winding the rope on the reel, the stop 39 on the ring-gear 15 will 10 be brought back to its original position, plus a difference as explained before and which represents the difference between the faces of the stops 38 and 39 in Figs. 2, 6 and 7. As the stop 39 approaches its original position 15 the engaging point of the latch 35 will begin to depress by action of the spring 37 as soon as the engaging point reaches one end of the slot in the disk 15 and indicated by numeral 42. As the disk 15 continues to 20 rotate in the direction S as indicated thereon the latch 35 will drop lower into the slot in the member 15 and until the stop 39 engages with the end of the latch 35 when rotation will be stopped. At this particular instant 25 the members 9 and 15 will bear the relative positions as indicated in Fig. 6.

To complete the setting of the retrieving mechanism it is only necessary to slack up 30 on the rope slightly, allowing the power in spring which has been winding up during the setting operation to cause the disk 9 to rotate in the direction R indicated thereon, but this rotation is only equal to that of the difference between the faces of the stops 38 35 and 39 as shown in Figs. 2, 6 and 7, at the end of which rotation the stop 38 in Fig. 6 will have engaged the end of the latch 35 as shown in Fig. 7 and in which position the retrieving members will be locked against rotation in either direction, except to the extent of the distance between the stops 38 and 39. (See Figs. 2 and 7).

The disk, however, is still in engagement with the drum 9 and to release the same it 45 is only necessary to slack up a little more upon the trolley rope in which case the spring 20 will cause the reel to rotate in a rope-winding direction while the member 9 is held stationary and this will continue until the rib 32 is out of engagement with the 50 rib 33 whereupon the spring 27 will draw the interlocking dog inward and out of all further engagement with the retrieving disk 9 until the dog has again been thrown outward 55 and into engagement with the retrieving disk 9 under centrifugal force. (Fig. 7 shows dog on point of releasing). If the tension against which the retrieving mechanism operates is considerable at the end of 60 the retrieving operation, then this must be taken into consideration in adjusting the mechanism and this is the case when applied to a trolley retriever.

As the tension in the trolley rope causing 65 it to rise is of a considerable amount, it

is necessary to properly balance the power spring in my device against that of the tension in the trolley pole spring when the trolley pole has been drawn down a proper amount and this can be accomplished after 70 one or two trials by setting the retrieving mechanism for a number of revolutions in excess of that required to draw the pole the proper distance below the level of the trolley wire. It will be readily understood that if 75 one starts with no tension on the power spring 4 and the device is set for four revolutions of the retrieving member 9 that when the device is properly connected to a trolley pole which has a spring action in opposition 80 to that of the power spring 4, that the retrieving device will draw the trolley pole down until the tension in the springs of the two devices opposing each other is at a balance. This might be found to be equal 85 to two turns of the retrieving disk; that is the power spring must be wound up two turns in order to balance the tension of the spring trolley pole and if it requires four turns of the reel to bring the trolley down a 90 sufficient distance, then the mechanism would be set to retrieve two plus four turns or six turns of the retrieving disk.

If this example should be found to be the case in actual practice then it would be only 95 necessary to set all the devices for six turns with no tension on the power spring and then in actual operation the trolley pole will be brought down in each case a distance equal to four turns of the retrieving disk. 100 If my retrieving mechanism is applied to a device which has very little force opposing the power spring 4 then the precautions just mentioned in setting the device in order to adjust for an opposing spring tension as in 105 a trolley pole are not necessary.

It is also possible to set the device for any fraction of a whole revolution by following 110 out the same principle in its setting as given above.

It is therefore believed that the present 115 invention provides a simple and practical device adapted to accomplish, among others, all the advantages and objects above set forth.

Without further analysis, the foregoing will so fully reveal the gist of this invention that others can by applying current knowledge readily adapt it for various applications without omitting certain features 120 that, from the standpoint of the prior art, fairly constitute essential characteristics of the generic or specific aspects of this invention, and therefore such adaptations should and are intended to be comprehended 125 within the meaning and range of equivalency of the following claims.

What I claim is:

1. A reeling device comprising in combination a casing, a retrieving member there- 130

in, a spring to rotate the member in a spring unwinding direction, a lock member engaging the retrieving member and preventing rotation of the retrieving member in a spring unwinding direction and a rotatable member rotating about the same axis as the retrieving member and inter-connected with the retrieving member and engaging the lock member and preventing engagement of the lock member and retrieving member until the retrieving member has been rotated a predetermined number of revolutions to wind the spring to a predetermined tension.

2. A reeling device comprising in combination a casing, a retrieving member therein, a spring to rotate the retrieving member in one direction, a lock member engaging the retrieving member and preventing rotation of the retrieving member in the same direction and a rotatable member rotating about the same axis as the retrieving member and inter-connected with the retrieving member and engaging the lock member and preventing the rotation of the retrieving member beyond a predetermined number of revolutions.

3. A reeling device comprising in combination a casing, a retrieving mechanism therein, a spring adapted to rotate the mechanism in one direction, the retrieving mechanism comprising two members inter-connected to always rotate simultaneously but relatively to each other about the same axis in either direction, a lock member, means on the retrieving mechanism adapted to engage the lock member to prevent the rotation of the retrieving mechanism in either direction after a predetermined number of revolutions of the retrieving mechanism in a spring winding direction.

4. A reeling device comprising in combination a casing, a retrieving mechanism therein, a spring secured to and adapted to rotate the mechanism in one direction, the retrieving mechanism comprising two members inter-connected to always rotate simultaneously but relatively to each other about the same axis in either direction, a lock member adapted to engage both rotatable members to prevent the rotation of either member in either direction after a predetermined amount of rotation of either member in the operation of winding the spring.

5. A reeling device having in combination a casing, two rotatable members inter-connected and arranged to rotate simultaneously and relatively to each other about a common axis, separate means to rotate the members in either direction, a lock member adapted to alternately engage the rotatable members and prevent rotation of the members until released and means on one rotatable member to engage the lock member to prevent engagement of the lock member with the other rotatable member until a pre-

determined number of turns of the other member have been obtained.

6. A reeling device comprising in combination a casing, a retrieving mechanism comprising two rotatable members interconnected and arranged to rotate simultaneously but relatively to each other about the same axis, separate means to rotate the retrieving mechanism in either direction and a lock member to engage one of the rotatable members to prevent rotation after a predetermined amount of rotation of the retrieving mechanism in one direction and to engage the other retrieving member to prevent, independent of aid from the first member, rotation of the retrieving mechanism in the other direction until the lock is released.

7. A reeling device comprising in combination a casing, a retrieving mechanism therein, a power spring secured to and adapted to rotate the mechanism in one direction when wound, the retrieving mechanism comprising two members rotatable about the same axis relatively to each other and to the casing, a lock member to engage each of the rotatable retrieving members, holding means on each rotatable member to engage the lock member at a predetermined spring tension, and inter-connecting mechanism between the rotatable members whereby the angular relation between the holding means on the rotatable members can be changed to obtain a predetermined spring tension in rotating the retrieving mechanism in a spring winding direction.

8. A reeling device having in combination a casing, a retrieving member mounted therein to rotate, a spring tending to rotate the retrieving member in one direction, a lock member, means on the retrieving member to engage the lock member to prevent rotation in the same direction, a member rotating about the axis of the retrieving member and inter-connected therewith and having means engaging the lock member to prevent, independent of aid from the retrieving member, the rotation of the retrieving member in the other direction.

9. A reeling device comprising in combination a casing, a retrieving mechanism therein, a spring adapted to rotate the mechanism in one direction when wound, the retrieving mechanism comprising two inter-connected members, an adjusting member and a retrieving member, both relatively rotatable about the same axis in either direction and having the retrieving member secured to the spring, a lock member adapted to engage the retrieving mechanism to prevent rotation in either direction, means on the adjusting member to engage the lock member to prevent rotation of the retrieving mechanism in a spring winding direction beyond a predetermined spring tension and

means on the adjusting member to prevent engagement of the lock and retrieving member until the predetermined amount of rotation of the retrieving member in a spring winding direction has been made.

10. A reeling device comprising in combination a casing, a retrieving mechanism therein comprising two inter-connected members relatively rotatable about the same axis in either direction, a spring adapted to rotate the mechanism in one direction, a rope winding reel adapted to engage and rotate the retrieving mechanism in the opposite direction when the rope is unwound therefrom 15 a lock member, means on one of the retrieving members to engage the lock member and prevent rotation in one direction and means on the other retrieving member to engage the lock member and prevent, independent 20 of aid from the first member, rotation in the other direction.

11. A reeling device comprising in combination a casing, a retrieving mechanism therein comprising two inter-connected 25 members relatively rotatable about the same axis in either direction, a spring adapted to rotate the mechanism in one direction, a rope winding reel adapted to engage and rotate the retrieving mechanism in the opposite direction when rope is unwound therefrom, a lock member, means on one of the retrieving members to engage the lock member and prevent rotation in one direction and means on the other retrieving 30 member to engage the lock member and prevent rotation in the other direction and means on one of the members to prevent engagement of the lock member with either of the stop means on the retrieving members 35 until a predetermined amount of rotation of the retrieving mechanism has been made in a spring winding direction.

12. A reeling device comprising in combination a casing, a retrieving member 45 therein, a spring adapted to rotate the retrieving member in one direction when wound, a lock member adapted to engage stop means on the retrieving member to hold the retrieving member against rotation by 50 the spring when the spring has been wound to a predetermined tension, an adjusting member rotatable about the same axis as the retrieving member and inter-connected therewith to rotate relatively to and simultaneously with the retrieving member and at a different rate of speed stop means on the adjusting member to engage the lock member to determine the number of turns of the retrieving member in a spring winding direction 55 and means to indicate the proper angular distance between the stop means on the retrieving and adjusting members to secure the predetermined number of turns of the retrieving member.

65 13. A reeling device having in combina-

tion a casing, a rotating member, a spring connected to the rotating member to rotate it in one direction, a second member mounted to rotate about the same axis as the first rotating member and to rotate in unison therewith, a single lock member engaging the first rotating member to prevent rotation by the spring and engaging the second rotating member to prevent the rotation of the first member in a direction opposite to that urged by the spring, independent of aid from the first rotating member and after a predetermined number of turns of the first rotating member and means to automatically release the lock member from engagement with the first member to permit the spring to function.

14. A reeling device comprising in combination a casing, a retrieving mechanism mounted to rotate therein, a spring arranged to rotate the retrieving mechanism in one direction, the retrieving mechanism comprising two inter-connected members relatively rotatable about the same axis in either direction one a retrieving member to which the spring is attached and the other an adjusting gear to control the winding limit of the spring and gearing mounted independent of the retrieving mechanism and inter-connecting the retrieving member and adjusting gear to cause them to rotate simultaneously at a predetermined relative speed, a lock member and means on the adjusting gear to coact with the lock member to prevent rotation of the retrieving member after a predetermined number of revolutions in a spring winding direction.

15. A reeling device comprising in combination a casing, a reel rotatively mounted therein to receive a rope, a retrieving member mounted to rotate in the casing, a spring to rotate the retrieving member in one direction, an adjusting gear mounted to rotate about the same axis as the retrieving member, a pinion mounted independent of the adjusting gear and retrieving member and inter-connecting the timing gear and the retrieving member to cause them to rotate simultaneously at a predetermined relative speed, a lock member, a stop on the adjusting gear and on the retrieving member to engage the lock member to lock them against rotation, the stop on the adjusting gear being so positioned relatively to the stop on the retrieving member as to limit the revolutions of the retrieving member to a predetermined value in a spring winding direction and means on the reel to automatically trip the lock between the lock member and the retrieving member and interconnect the reel and retrieving members together when the reel is rotated at an abnormal speed.

16. A reeling device having in combination a casing, a retrieving member mounted therein to rotate, spring mechanism tending

to rotate said member in one direction, a pinion secured to the member, a ring gear mounted in the casing and in axial alignment and arranged to rotate simultaneously with the retrieving member, a member rotatably connecting the gear and pinion, and means associated with the casing for engaging the retrieving member and gear to prevent rotation in either direction after a predetermined number of revolutions of the retrieving member in a spring-winding direction.

17. A reeling mechanism having in combination therewith a casing, a retrieving member therein, spring mechanism to rotate said member in one direction, a rotatable member coupled with the retrieving member to rotate simultaneously therewith, connecting means between said rotatable member and retrieving member, a holding member associated with the casing to coact with the rotatable member to prevent rotation of the retrieving member after a predetermined number of turns in a spring-winding direction 25 when resetting said member and operating to engage and hold the retrieving member, when reset, against rotation by the spring mechanism, and means for varying the angular position of the retrieving member and rotatable member whereby the predetermined number of turns to reset the retrieving member can be varied.

18. A reeling device having in combination therewith a casing, a retrieving member therein, spring mechanism for rotating said member in one direction, a rotatable member arranged in the casing for rotation relatively to and in a predetermined relation to the retrieving member, connecting means between the retrieving member and rotatable member, the retrieving member and rotatable member each provided with locking means, and a holding member associated with the casing to coact with the locking means of the rotatable member thereby to limit rotation of the retrieving member to a predetermined amount when resetting said member to normal position and to coact with the locking means of the retrieving member 50 to hold the latter against rotation by the spring mechanism when in normal position.

19. A reeling device comprising in combination therewith a retrieving mechanism comprising two inter-connected members relatively rotatable about the same axis in either direction, means for rotating the members in either direction simultaneously and a lock member engaging one of the rotatable members to check rotation of both 60 members independent of aid from the other member, in one direction and engaging the other rotatable member to check rotation of both members, independent of aid from the first member, in the opposite direction.

65 20. A reeling device having in combina-

tion a casing, a retrieving mechanism therein, a spring adapted to rotate the retrieving mechanism, the retrieving mechanism comprising two members relatively rotatable about the same axis, a lock member adapted to engage the retrieving members to prevent their rotation in either direction, and a speed changing mechanism inter-connecting the retrieving members and mounted independent thereof and adapted to cause the retrieving members to rotate simultaneously at different speeds, one of the retrieving members adapted to limit the rotation of the retrieving mechanism in a spring winding direction to a predetermined amount.

21. A reeling device comprising in combination a casing, a retrieving mechanism therein, a spring secured to and adapted to rotate the retrieving mechanism in one direction, the retrieving mechanism comprising two rotatable members rotating about a common axis and a speed changing mechanism inter-connecting the rotatable members to cause the members to rotate at different speeds, a lock member adapted to engage the retrieving mechanism to prevent the rotation of the retrieving mechanism in either direction after a predetermined number of revolutions of the retrieving mechanism in a spring winding direction.

22. A reeling device comprising in combination a casing, a retrieving mechanism, a spring secured to and adapted to rotate the retrieving mechanism in one direction, the retrieving mechanism comprising two rotatable members rotating about a common axis and a direction changing mechanism inter-connecting the rotatable members to cause the members to rotate in opposite directions, a lock member adapted to engage the retrieving mechanism to prevent the rotation of the retrieving mechanism in either direction after a predetermined number of revolutions of the retrieving mechanism in a spring winding direction.

23. A reeling device comprising in combination a casing, a retrieving mechanism therein, a spring secured to and adapted to rotate the retrieving mechanism in one direction, the retrieving mechanism comprising two rotatable members rotating about a common axis, a locking member, stop means on each of the rotating members to engage the locking members to prevent rotation of the retrieving mechanism after a predetermined number of turns in a spring winding direction, to prevent engagement of the locking and stop means until the required number of turns has been reached and to hold the retrieving mechanism against rotation in a spring unwinding direction until released and mechanism inter-connecting the retrieving members whereby the angular distance between the stop means on the re- 130

trieving members can be changed to change the number of turns of the retrieving mechanism in a spring winding direction.

24. A reeling device comprising in combination a casing, a retrieving mechanism therein, a spring adapted to rotate the mechanism in one direction when wound and released, the retrieving mechanism comprising two inter-connected members consisting of an adjusting member and a retrieving member both relatively rotatable about the same axis in either direction, a lock member adapted to engage the retrieving mechanism to prevent rotation in either direction, means on the retrieving member to engage the lock member to prevent rotation of the retrieving mechanism under action of the spring tension, means on the adjusting member to check rotation of the retrieving mechanism in a spring winding direction after a predetermined spring tension has been reached and means on the adjusting member to prevent engagement of the lock and retrieving members until the predetermined spring tension has been reached through rotation of the retrieving mechanism.

25. A reeling device comprising in combination a casing, a retrieving mechanism therein, a drum upon which to wind a rope, automatic means acting under abnormal speed of the drum to connect the drum and retrieving mechanism to rotate in unison, a spring adapted to rotate the retrieving mechanism in one direction, a lock member adapted to engage and arrest the rotation of the retrieving mechanism in either direction and to be engaged by the automatic means, the retrieving mechanism comprising two rotatable members inter-connected and rotating relatively about the same axis, and adapted to rotate in one direction under action of the spring to wind the rope on the drum and to rotate in the opposite direction to wind the spring when the rope is unwound from the drum and means on the retrieving mechanism to engage the lock member to arrest rotation of the drum in a rope unwinding direction at a predetermined spring tension and to prevent rotation of the retrieving mechanism under spring action until the automatic means has engaged and released the lock member.

nation a casing, a retrieving mechanism therein, a drum upon which to wind a rope, 30 automatic means acting under abnormal speed of the drum to connect the drum and retrieving mechanism to rotate in unison, a spring adapted to rotate the retrieving mechanism in one direction, a lock member 35 adapted to engage and arrest the rotation of the retrieving mechanism in either direction and to be engaged by the automatic means, the retrieving mechanism comprising two rotatable members inter-connected and rotating relatively about the same axis, and adapted to rotate in one direction under action of the spring to wind the rope on the drum and to rotate in the opposite direction to wind the spring when the rope is unwound from the drum and means on the retrieving mechanism to engage the lock member to arrest rotation of the drum in a rope 40 unwinding direction at a predetermined spring tension and to prevent rotation of the retrieving mechanism under spring action until the automatic means has engaged and released the lock member.

In testimony whereof I affix my signature.

FRANK A. KLOHS.
